UNITED STATES PATENT OFFICE

BEATRICE E. TIBBITS, OF NEW YORK, N. Y.

UNDERGARMENT

Application filed July 7, 1930. Serial No. 465,946.

This invention relates to undergarments and is particularly directed to an improved woman's combination foundation garment or corselet, having a brassière portion, a girdle 5 portion and a hose support.

An object of this invention is to provide an undergarment of the character described of improved construction, which shall aid in maintaining the wearer's body posture erect 10 and which shall yet comfortably fit the wearer and be easy to put on or remove from the body and permit unrestricted body movements.

Another object of this invention is to provide an improved combination undergarment 15 of the character described which may easily and quickly be adjusted to fit various body shapes and to vary the tension applied to the garment.

A still further object of this invention is to provide a garment of the character described which shall have means for improving the shape of the wearer, to produce an attractive foundation for the outer garments, 20 without causing discomfort.

A still further object of this invention is to provide an improved combination undergarment of the character described comprising few and simple parts, comparatively inexpensive 25 to manufacture, durable in construction, comfortable to wear, easily put on and taken off and which may yet be inconspicuously worn and practical and efficient to a high degree in use.

Other objects of this invention will in part 30 be obvious and in part hereinafter pointed out.

The invention accordingly consists in the features of construction, combinations of elements, and arrangement of parts which will 35 be exemplified in the construction hereinafter described, and of which the scope of application will be indicated in the following claims.

In the accompanying drawings, in which is shown one of the various possible illustrative embodiments of this invention,

Fig. 1 is a front perspective view of the undergarment embodying the invention 40 shown in position on the wearer;

Fig. 2 is a rear perspective view of the garment as worn;

Fig. 3 is a cross-sectional view of the garment taken on line 3—3 of Fig. 1;

Fig. 4 is a fragmentary perspective detail 45 view of a portion of the garment; and

Fig. 5 is a front elevational view of the garment spread flat.

Referring now in detail to the drawings, 50 Fig. 1 designates an undergarment embodying the invention here shown in the form of a woman's foundation combination garment or corselet. The garment is preferably made in one-piece of any suitable flexible cloth or fabric, no bones or steels or similar stiffening members being employed in the construction thereof. The garment comprises a front section 11 adapted to cover substantially the front of the body from just beneath the bust to the thighs, a small elastic triangular gusset 12 being incorporated into the central bottom edge portion of said section to permit movement of the body. The upper portion of said section 11 preferably terminates in a pointed portion 14 to each side of which 55 there is seamed as by stitches 11a, a suitably fashioned, curved breast confining section 15. Sewed to the opposite side edges 13 of said front section 11, are elongated sections 16 seamed to said sections 15 and extending to 60 the lower edge of the garment. Seamed to the side edges 16a of each of said sections 16 are sections 17 likewise sewed to the underedges of said bust confining portions 15 and extending to the bottom edge of the garment. 65 As shown in the drawings, when the garment is worn, said sections 17 are disposed at the sides of the wearer's body, from substantially beneath the arms to below the hips. Adjacent said sections 17 and seamed to the 70 outer edges 17a thereof, the garment is provided with sections 18 extending to the top edge of the garment and adapted to be disposed below the arm pits of the wearer and around the rear of the body. Extending from 75 and seamed to each of said sections 18, as at 18a, is a portion or section 19, adapted to be wrapped around the rear of the wearer's body, the upper edge of said sections being diverged downwardly. The lower portion 80

100

of each of said sections 19 is adapted to cover the buttocks, and the lower edge 21 thereof curves upwardly, said sections 19 terminating in vertical outer edge portions 23 adapted to be disposed just above the hips of the wearer.

Attached to the outer edges 23 of said section 19 are sections 25 preferably made of elastic material. Attached to the outer edge 27 of each of said sections 25, is a strip 28 carrying a plurality of spaced fastening members, such as hooks 29, for the purpose hereinafter described. A second strip 30 similar to strip 28 is attached to each strip 25 in substantially parallel spaced relation to said strip 28. Said strip 30 likewise carries a plurality of spaced fastening members, such as hooks 31, for the purpose hereinafter described, the hooks 29 and 31 preferably being similar in number and similarly spaced.

The position of the garment on the wearer's body is illustrated in Figs. 1, 2, and 3. It will be noted that the garment is wrapped around the body and that the outer end portions of the garment cross each other at the back and are folded one over the other in overlapping or superimposed relation. To permit the garment to be wrapped as shown, the same is formed on one side thereof adjacent one of the seams 17a with a slit or opening 35 adapted to receive the elastic section 25 extending from the opposite side of the garment therethru. Attached to the outer surface of the garment, adjacent each of the seamed edges 16a are vertical strips 36 carrying a plurality of complementary fastening members such as eyes 37 adapted to engage the hooks 29 on the strips 28. It will now be understood that the section 25 at one end of the garment is first wrapped around the body and passed thru the slit 35, and attached to the outer side of the garment by means of the eyes 37 on the strip 36 close to the said slit. The opposite end of the garment may then be wrapped over the already wrapped end attached portion of the garment, and attached to the eyes 37 on the other strip 36. The garment is thus encircled around the body and attached to the intermediate portions of the garment for bracing the body and aiding in maintaining the same in proper and erect posture.

The number of eyes carried by each of the strips 36 and 39 is greater than the number of hooks 29 carried by each of the strips 28 and likewise greater than the number of hooks 31 carried by each of the strips 30. With this construction, the position of the garment may be adjusted since the set of hooks 29 may engage various sets of eyes 37. For the purpose of illustration, each of the strips 36 and 39 is provided with seven eyes, whereas each of the strips 28 and 30 is provided with only five hooks. The five hooks 65 may engage either the upper five eyes, the

intermediate five eyes or the lowermost five eyes. In this manner, the position of the garment and tension produced upon interengaging the hooks and eyes may be adjusted to suit various conditions and preferences. Should the wearer desire to have the garment tightly wrapped around her the inner sets of hooks 31 may be utilized instead of the outer sets of hooks 29. Obviously, the inner sets of hooks 31 may be also utilized, should the elastic section 25 stretch after long use.

It will now be clear that the garment serves to constrict and support the waistline, abdomen and hips of the body as well as confine the bust and buttocks. The garment may be supported from the shoulders by means of shoulder straps 50 preferably provided with a plurality of button holes 51 on each end thereof for buttons 52 located at the upper edge portion of the garment. The length of the shoulder strap may thus be adjusted as desired. The straps also may be provided with elastic sections 53 whereby the straps may fit various sized persons.

The garment is furthermore provided with means for supporting the hose. To this end, there is attached to the front of the garment, adjacent the bottom edge thereof, on each side of the section 11, and aligned with the side edges 13 thereof, elastic hose supporting straps 55 of usual construction. Attached to the lower outer curved corner of each of the sections 19 is a strap 56, said straps being attached to extend outwardly and downwardly or in an inclined or oblique direction for the purpose hereinafter described. Upon applying the garment to the body, it will be noted that sections 18 and 19 overlap each other at the rear of the body. Thus in this manner, the hose supporting strap 56 attached to one side of the garment, after wrapping on the body, extends downwardly and is inclined towards the opposite side of the body and may hence be attached to the stocking on the opposite leg. In other words, upon putting on the garment, the hose strap 56 extending on the right of the garment, by reason of the folding or wrapping of said garment around the body and by reason of the inclination of the strap, may be attached to the stocking on the left leg. This manner of attachment serves to draw the garment tightly around the buttocks for confining and constricting the same, thus aiding in producing a foundation for outer garments. By reason of the overlapping portions of the garment around the rear of the body and the buttocks, increased pressure is exerted on said body for aiding in retaining the body in constricted shape.

It will be noted that no bones, steels, or the like tensioning members are employed, the garment hence being highly practical and efficient in use without causing discomfiture or interfering materially with the movements of the body.

A reinforcing flexible member 60 may be sewed to the inner face of the garment and as by stitching to the seamed edges 13 as shown in Fig. 3.

It will also be seen that the garment may be spread flat and easily put on and taken off. For putting on the garment the arms are first inserted thru the loops formed by the shoulder straps, and the outer end portion of the garment opposite to the side in which the slit is located, is then wrapped rearwardly about the back, and passed thru the slit and attached to the eye fasteners adjacent to said slit. The other end portion is then wrapped around the back in overlapping relation to the already wrapped portion of the garment, and attached to the other set of eye fasteners. To remove the garment the above steps are merely reversed.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A garment of the character described comprising a member having a central portion adapted to cover a portion of the wearer's body, and portions extending outwardly from said first portion adapted to be wrapped about the body in overlapping relation, said garment having a slit therein for receiving the end of one of said outwardly extending portions therethru, and means for attaching said end to said garment, said means comprising a row of fastening members attached to the outer surface of said garment, and a row of complementary fastening members attached to said end adapted to cooperate with said first row of fastening members, the fastening members in one row being unequal in number to that of the fastening members on said other row.

2. A garment of the character described comprising a member made of flexible material having a portion adapted to cover the front of the body, outwardly extending portions adapted to be wrapped about the body in overlapping relation to each other, and portions extending downwardly from said outwardly extending portions, for covering the rear of the body and the buttocks.

3. A garment of the character described comprising a member made of flexible material having a portion adapted to cover the front of the body and confine the bust, out-

wardly extending portions adapted to be wrapped about the body in overlapping relation to each other, and portions extending downwardly from said outwardly extending portions, adapted to cover the rear of the body and the buttocks, and a hose strap attached to each of said downwardly extending portions.

4. A garment of the character described comprising a member made of flexible material having a portion adapted to cover the front of the body and confine the bust, and outwardly extending portions adapted to be wrapped about the body in overlapping relation to each other, said overlapping portions being adapted to cover the rear of the body and the buttocks, and a hose strap attached to each of said outwardly extending portions, said straps extending downwardly and outwardly from said outwardly extending portions.

5. A woman's foundation undergarment comprising a member made of flexible material adapted to be spread flat and having bust confining portions, a central abdominal confining portion, portions extending from the sides of said central portion and portions extending downwardly from said last named portions adapted to cover the buttocks, said garment having an opening on one side of said central portion adapted to receive the portion extending from the opposite side of said central portion.

6. A woman's foundation undergarment, comprising a central portion, portions extending outwardly from the sides of said central portion, a pair of vertical parallel rows of fastening members attached adjacent the end of one of said extending portions, said garment having a slit adapted to receive said end therethru, and a row of complementary fastener members secured adjacent said slit adapted for coaction with one of the other of said rows of fasteners.

7. A woman's foundation undergarment comprising a central portion, portions extending outwardly from the sides of said central portion, and a pair of parallel rows of fastening members attached adjacent the end of one of said extending portions, said garment being formed with a slit, and a row of complementary fastener members secured to said garment adjacent said slit, the number of fastener members on each of the first two rows being equal to each other, and different from the number of fastener members in the last mentioned row.

8. A woman's undergarment comprising a member made of flexible material adapted to be spread flat having a central portion adapted to cover the front of the wearer's body, portions extending outwardly from said central portion adapted to be wrapped rearwardly about the body in overlapping relation, portions for covering the buttocks, and means for attaching said outwardly ex-

tending portions to intermediate portions of said garment for retaining the garment in wrapped condition about said body.

9. A woman's undergarment comprising a member made of flexible material adapted to be spread flat having a central portion adapted to cover the front of the wearer's body and portions extending outwardly from said central portion adapted to be wrapped rearwardly about the body in overlapping relation, and means for attaching the end portion of said outwardly extending portions to intermediate portions of said garment for retaining the garment in wrapped condition
- 10 about said body, said means comprising a row of fastener members adjacent each of said end portions and rows of fastening members on said garment adapted to cooperate with said first mentioned rows of fastening members.

10. A woman's undergarment comprising a member made of flexible material adapted to be spread flat having a central portion adapted to cover the front of the wearer's body and portions extending outwardly from said central portion adapted to be wrapped rearwardly about the body in overlapping relation, and means for attaching the end portions of said outwardly extending portions to intermediate portions of said garment for retaining the garment in wrapped condition about said body, said means comprising a row of fastener members adjacent each of said end portions and rows of fastening members on said garment adapted to cooperate with said first mentioned rows of fastening members, the number of fastening members on each of the rows of said end portions being different from the number of fasteners in each of said other rows.

In testimony whereof I affix my signature.
BEATRICE E. TIBBITS.
